STRAP COUPLER

Leo Roseman, Newark, N. J., the assignee of the inventor, filed

Application July 20, 1934, Serial No. 736,142

4 Claims.

(Cl. 24—226)

This invention relates, generally, to means for detachably connecting straps such as those used in women's clothing, and the invention has reference more particularly to a novel construction 5 of strap coupler, the said coupler being adapted to be readily attached to straps for reliably interconnecting the same.

Strap couplers or connections heretofore used in women's clothes, such as brassières and other under garments, have quite generally been, more or less bulky so that the same are uncomfortable to wear and also tend to distort or disfigure the outer garment of the wearer. Also, many of these couplers or connecting means are difficult 10 to fasten and unfasten and at times the same become unfastened accidentally which is highly undesirable.

The principal object of the present invention is to provide a novel strap coupler that is positive 20 in its holding action, will not disengage accidentally and is substantially flat and of minimum bulk and area so as to lie in the plane of the connected straps and thereby rest flat against the back or other part of the body of the wearer, as well as to present a flat face to overlying garments, the said coupler being adapted to enable 25 the ready sliding adjustment of the connected straps therethrough when desired, whereby the coupler enables the apparel employing the same to automatically accommodate the body contour and movements of the wearer.

Another object of the present invention lies in the provision of the novel strap coupler of the 30 above character that is readily engaged and disengaged, the said coupler having interlocking means for preventing the accidental disengagement of the same.

Still another object of the present invention is to provide a novel strap coupler of the above 35 character that is of simple, rugged construction and dependable in use.

Other objects of this invention, not at this time more particularly enumerated, will be clearly understood from the following detailed description 40 of the same.

The invention is clearly illustrated in the accompanying drawing, in which:—

Fig. 1 is a fragmentary view in elevation illustrating the novel coupler of the present invention used for connecting looped strap end portions.

Fig. 2 is a plan view of the connection shown in Fig. 1.

Fig. 3 is an enlarged sectional view taken along

line 3—3 in Fig. 1, looking in the direction of the arrows.

Fig. 4 is a rear view of the structure shown in Fig. 1.

Figs. 5, 6, 7, 8 and 9 illustrate the manner of connecting or disconnecting the strap coupler.

Fig. 10 illustrates the strap coupler adapted for enabling the adjustment of the length of the straps connected thereby.

Fig. 11 is an enlarged sectional view taken along line 11—11 in Fig. 10, and

Figs. 12 and 13 are enlarged views of the coupler members.

Similar characters of reference are employed in said views, to indicate corresponding parts.

Referring now to the said drawing, the reference numerals 1 and 2 designate looped strap end portions that are interconnected by the novel strap coupler of this invention. This strap coupler comprises two substantially flat members 3 and 4. Coupler member 3 is of substantially rectangular shape and is provided with a rectangular aperture or slot 5 for loosely receiving the strap 1, the strap 1 being readily slideable through slot 5 as when adjusting a garment upon the 25 body of the wearer.

Coupler member 3 is provided, substantially midway of its height, with a hook 6, the said hook being shown as formed by turning or folding over a tab provided on member 3. The spacing of the flat folded over portion of hook 6 from the main body of member 3 is slightly greater than the thickness of coupler member 4 for accommodating this latter member. Coupler member 4 is also of substantially rectangular shape and 35 has a rectangular aperture or slot 7 therein for loosely receiving the strap 2, which strap is readily slideable through slot 7 as when adjusting a garment upon the body of the wearer.

One end of slot 7 is transversely enlarged at 8 to provide a receiving opening for the hook 6 as will further appear, the dimensions of receiving opening 8 being greater than the dimensions of the hook 6 so as to enable the ready insertion and removal of the latter through this opening. Receiving opening 8 communicates with a locking aperture or slot 10. Locking aperture 10 has an inner edge 11 extending parallel to the edge 12 of the receiving opening 8. Inner edge 11 is inwardly offset from the edge 12 a distance 50 slightly greater than the thickness of the bight portion 9 of hook 6, thereby enabling this hook to be slid from receiving opening 8 into locking aperture 10. Locking aperture 10 has an outer edge 13 extending substantially parallel to edge 55

12 and to edge 11. Outer edge 13 is outwardly offset from receiving opening edge 12, thereby forming a transverse lock or stop shoulder 14 between these edges. The outer edge 13 is slightly longer than the height of hook 6 and the width of stop shoulder 14 is substantially equal to the thickness of the bight portion 9 of the hook 6, so that with hook 6 inserted into locking aperture 10 as shown in Fig. 1 the same is confined 10 between stop shoulder 14 and the bottom of aperture 10, thereby preventing vertical movement of the hook 6 and hence preventing its accidental disconnection from coupler member 4. The tension or pull of straps 1 and 2 upon coupler members 3 and 4 serves to hold the bight 9 of the hook in engagement with outer edge 13 of locking aperture 10.

Assuming that it is desired to disconnect coupler members 3 and 4, these two members are 20 moved toward one another as indicated by the arrows in Fig. 5, thereby causing the bight 9 of hook 6 to disengage outer edge 13 and to move into abutting relation to the inner edge 11 of the locking aperture 10. During this movement of 25 the hook 6, its upper edge moved out of engagement with the stop shoulder 14 so that the coupler member 3 may now be moved upwardly with respect to coupler member 4 as illustrated in Fig. 6. Continued upward movement of coupler member 3 will cause the bight 9 of hook 6 to pass 30 out of locking aperture 10 and into receiving opening 8. The coupler members 3 and 4 may now be pushed further toward each other as shown by the arrows in Fig. 7 so that the hook 35 6 disengages the coupler member 4. The coupler members may now be completely separated by merely moving the same apart as shown by the arrows in Fig. 8, thereby disconnecting the straps 1 and 2.

If it is desired to again connect the coupler members 3 and 4 it is merely necessary to insert hook 6 into receiving opening 8 and then move the coupler members apart slightly so that the bight 9 of hook 6 engages edge 12 of the receiving 40 opening. Coupler member 3 is then moved downwardly with respect to coupler member 4, so that hook 6 enters locking aperture 10. Continued downward movement of the hook causes the same to ride off of edge 12 and to engage the 45 edge 13 of the locking aperture, the shoulder 14 and the bottom edge of the locking aperture 10 acting in connection with the tension of straps 1 and 2 to confine and lock the hook 6 in place and preventing accidental disconnection of the 50 same from coupler member 4 regardless of the movements of the wearer.

It will be noted that the coupler members 3 and 4 can only be separated by a compound movement of these members, i. e., first these members 60 must be moved toward each other, then vertically with respect to one another, then further toward each other and then transversely apart from one another. This compound movement, though easily performed manually, is substantially impossible of execution accidentally especially since the straps connected by the coupler are usually under slight tension, so that in use it is found that the novel coupler does not become disengaged accidentally.

In some instances it is desirable to adjust the 70 length of one or both of the straps connected by the coupler, in which case the width of either or both of the coupler members 3 and 4, is increased and the same provided with an additional strap aperture. This is illustrated in Figs. 10 and 11

wherein the coupler member 3' is provided with an additional strap aperture 15 so that the end portion 16 of the strap 1' may be adjusted or passed through apertures 5 and 15 to vary the effective length of strap 1'. Corrugations 17 5 may also be provided on the coupler member 3' to aid in preventing accidental slipping of strap 1' through apertures 5 and 15.

If desired, instead of having the strap end portions 1 and 2 looped through the strap apertures 10 of the coupler members, resulting in two runs of the strap material being connected to each coupler member, but one run of strap material may be connected to either or both coupler members, if desired, by stitching the strap end portion to the 15 coupler member, preferably using zig-zag stitching.

As many changes could be made in the above construction and many apparently widely different embodiments of this invention could be made 20 without departing from the scope thereof, as defined by the following claims, it is intended that all matter contained in the above description or shown in the accompanying drawing shall be interpreted as illustrative and not in a limiting 25 sense.

I claim:—

1. A strap coupler of the character described comprising two substantially flat coupler members, said coupler members having means for adjustably connecting the same to straps, one of said coupler members having a hook and the other of said coupler members having an aperture therein for receiving said hook, said last named coupler member having a locking aperture communicating with said receiving aperture, said locking aperture having a recessed portion of a height equal to that of said hook and a width equal to the thickness of the bight portion of said hook for retaining the latter therein, whereby 40 movement of said hook from said receiving aperture into said locking aperture serves to secure said coupler members together and against accidental separation.

2. A strap coupler of the character described 45 comprising two substantially flat coupler members, said coupler members having means for adjustably connecting the same to straps, one of said coupler members having a hook and the other of said coupler members having an aperture 50 therein of greater size than the turned over portion of said hook for receiving the latter by transverse movement thereinto, said last named coupler member having a locking aperture communicating with said receiving aperture, said locking aperture having an outer edge portion of 55 a length equal to the height of the bight of said hook, said outer edge portion being offset from said receiving aperture thereby providing a locking recess having a stop shoulder for engaging 60 and retaining said hook therein.

3. A strap coupler of the character described comprising two substantially flat coupler members, said coupler members having means for adjustably connecting the same to straps, one of said coupler members having a hook and the other of said coupler members having an aperture 65 of greater size than the turned over portion of said hook for receiving the latter by moving said coupler members together while 70 holding them parallel to one another, said last named coupler member having a locking aperture communicating with said receiving aperture, said locking aperture being of smaller size than the turned over portion of said hook and arranged 75.

to receive said hook from said receiving aperture, said locking aperture having an outer edge portion, outwardly offset from said receiving aperture, said outer edge portion being of a length 5 equal to the height of the bight portion of said hook for receiving the latter and cooperating with said receiving aperture so as to require a compound movement of said coupler members when separating the latter.

- 10 4. A strap coupler of the character described comprising two substantially flat coupler members, said coupler members having means for suitably connecting the same to straps, one of said coupler members having a hook and the 15 other of said coupler members having an aperture therein of greater size than the turned over portion of said hook for receiving the latter, said last named coupler member having a locking aperture communicating with said receiving aper-

ture, said locking aperture being of smaller size than the turned over portion of said hook and arranged to receive said hook from said receiving aperture, said locking aperture having an outer edge portion thereof of a length equal to the 5 height of the bight of said hook and outwardly offset from the mouth portion of said locking aperture a distance equal to the thickness of the bight portion of said hook, to provide stop means to prevent accidental escape of said hook and consequent separation of said coupler members, said locking aperture having an inner edge portion inwardly offset from the outer edge of said receiving aperture a distance substantially equal to the thickness of the bight portion of said hook to 15 enable the entrance of the hook by endwise movement of the same into said locking aperture.

LEO ROSEMAN.
